UNITED STATES PATENT OFFICE.

FREDRICK E. PORTER, OF NEW DURHAM, NEW JERSEY, ASSIGNOR TO THE NATIONAL AUTOMATIC ACETYLENE GAS MACHINE COMPANY, OF NEW JERSEY.

ACETYLENE-GAS-GENERATING MACHINE.

SPECIFICATION forming part of Letters Patent No. 623,425, dated April 18, 1899.

Application filed February 10, 1898. Serial No. 669,744. (No model.)

To all whom it may concern:

Be it known that I, FREDRICK E. PORTER, a citizen of the United States, residing at New Durham, in the county of Hudson and State 5 of New Jersey, have invented certain new and useful Improvements in Gas-Generating Machines, of which the following is a full, clear, and exact specification.

My invention relates to gas-generating machines, and particularly to machines for generating acetylene gas.

The object of the invention is to provide suitable means for automatically regulating the supply of water to the calcium carbid during the operation of the machine in a positive manner by the rise and fall of the gasometer.

The invention is applicable for use in connection with any device where a delicate and positive regulation of the flow of a liquid is desired, and I desire to secure its use in all such instances, notwithstanding I have described the same herein in connection with an acetylene-gas machine.

In the accompanying drawings, in which I 25 have illustrated the invention as applied to an acetylene-gas-generating machine, Figure 1 is a sectional view of a machine, showing the invention in connection therewith. Fig. 2 is an enlarged detail view of the valve and its 30 connections with the gasometer, and Fig. 3 is an enlarged detail view of the thrust-rod and surrounding parts.

Referring more particularly to the drawings, A represents a suitable tank and a gasometer therein and adapted to rise and fall in the usual manner inside the tank, and communication between the gasometer and the tank being shut off from each other by any desirable means, preferably by a seal of water 40 between the two tanks, as is common in apparatus of this character.

R R are the retorts in which the calcium carbid is placed and in which is generated the acetylene gas by the addition of water thereto. A pipe B connects the retorts with the gasometer, and a pipe C leads from the gasometer to the place of consumption.

Thus far the apparatus described is substantially the same as is in common use in 50 various places, and I do not claim any nov-

elty in such construction, nor do I limit myself to any particular type of apparatus.

Attached to the gasometer and located either outside of the tank A or inside thereof, as shown in the drawings, is an actuating-rod F, which is suitably connected with the mechanism for controlling the flow of water to the retorts. In the present instance the water is located between the tank and the gasometer, and a pipe Q leads from said source 60 of water-supply to the retorts. In pipe Q is a valve, which in this instance comprises a cone-shaped seat L, a cone-shaped plug N, adapted to rest therein and having a vertical stem M of sufficient weight to normally keep 65 the plug in close fit with the valve-seat, and a support G, having formed thereon a tube J, which surrounds the valve-stem M and guides the latter in its movement. It is obvious that any form of valve—such, for instance, as the usual rotary plug shut-off valve—may be used in place of the one here described, and I therefore do not limit myself to this form, although for reasons to be hereinafter set forth I prefer this particular 70 construction in practice.

The actuating-rod F may, if preferred, be attached directly to the valve-stem or other part which operates the valve; but in practice I prefer to attach one end of the rod to 80 the lower end of the gasometer and the other end to a pivoted stud f, whereby the rod will be inclined from the side of the gasometer and will be located in a line oblique to the path of movement of the gasometer. Stud f 85 should be provided with means, such as a setscrew, to vary the inclination of the rod. A thrust-rod o, having a perforation in one end through which the actuating-rod passes, rests loosely in a supporting-sleeve k, formed upon 90 or adjacent to the tube J, and has an oblique surface or point which passes through a perforation in the upper part of stem M. The oblique surface may be formed upon the upper side only of the rod o or upon both the 95 upper and lower sides, if preferred.

In the operation of the device above described after the carbid has been placed in the retorts and a sufficient quantity of water allowed to enter the latter to generate enough 100

gas to raise the gasometer until the desired pressure of gas has been reached any further upward movement of the gasometer will cause rod F to pull back rod o, and thus 5 allow the heavy stem M to drop and close the valve, shutting off further supply of water and preventing the further generation of gas. The water may be allowed to enter the valve from its source of supply in any suitable 10 manner—such, for instance, as allowing it to flow through tube J around the stem M. When the pressure of gas in the gasometer drops and the gasometer begins to fall, the rod F will push rod o forward and cause the 15 valve-stem to be raised by the action of the oblique surface on the end of rod o. In most cases the weight of the valve-stem is sufficient to insure the valve closing when rod o is drawn back; but if the lower side of the rod 20 be provided with an oblique surface in a parallel plane with the upper surface the backward motion of rod o will have the same positive effect in forcing the valve-stem down as the forward motion of rod o has in forcing 25 it up, or, in other words, the action will be the same as that between rods F and o. While the machine is in operation and the gas is being drawn from the gasometer, the movement of the valve-plug N away from and toward 30 its seat L will be very slight, with the result that the water will flow down the sides of the cone-shaped plug and drop by drop pass into pipes P and Q. This is advantageous in that it insures a regular and thorough action of the 35 water upon the carbid.

It is apparent that the apparatus above described may be modified or various parts eliminated or substitutions made therefor without departing from the scope or spirit of 40 the invention, and I therefore do not wish to be understood as confining myself to the precise construction and operation here shown and described.

Having thus described my invention, I declare that what I claim, and desire to secure 45 by Letters Patent, is—

1. The combination with a valve having a stem, of a body adapted to reciprocate adjacent thereto and having an actuating-rod ob-

lique to the path of movement of said stem, 50 a thrust-rod having a perforation embracing said actuating-rod, and a connection between said thrust-rod and said stem, substantially as described.

2. The combination with a valve having a 55 perforated stem, of a body adapted to reciprocate adjacent thereto and having an actuating-rod oblique to the path of movement of said stem, and a thrust-rod having an oblique surface projecting into the perforation in the 60 valve-stem and a perforation embracing said actuating-rod, substantially as described.

3. The combination of a gasometer, a retort, a source of water-supply, a passage from 65 said source of water-supply to said retort, means for regulating the flow of water in said passage, a device for actuating said means, and an actuating-rod carried by the gasometer impinging against and operating said device and having a sidewise motion oblique to 70 the path of movement of the latter, substantially as described.

4. The combination of a gasometer, a retort, a source of water-supply, a passage from 75 said source of water-supply to said retort, a valve in said passage, a device for actuating said valve, and an actuating-rod carried by the gasometer impinging against and operating said device and having a sidewise motion oblique to the path of movement of the latter, 80 substantially as described.

5. The combination of a gasometer, a retort, a source of water-supply, a passage from 85 said source of water-supply to said retort, a valve in said passage having a vertical perforated stem, a thrust-rod having an oblique surface projecting into said perforation, and an actuating-rod carried by the gasometer impinging against and actuating said thrust-rod and having a sidewise motion oblique to the 90 path of movement of said thrust-rod, substantially as described.

In testimony whereof I affix my signature in presence of two witnesses.

FRED. E. PORTER.
